(57) **CLAIM**

The ornamental design for a storage rack, as shown and described.

DESCRIPTION

In a preferred embodiment, the nature of this product is a storage rack suitable for storage of items, for example, storage of food preparation items under a kitchen sink.

FIG. 1 is a right, top, front, perspective view thereof of a storage rack embodying my new design;

FIG. 2 is a front elevational view thereof, the rear elevational view thereof being a mirror image of the front shown;

FIG. 3 is a right side elevational view thereof;

FIG. 4 is a left side elevational view thereof;

FIG. 5 is a top plan view thereof; and,

FIG. 6 is a bottom plan view thereof.
